(57) **CLAIM**

The ornamental design for a beverage-holding pouch, as
shown and described.

DESCRIPTION

FIG. 1 is a front-perspective view of the beverage-holding pouch with shoulder strap, where the zipper and frontal-release straps are closed.

FIG. 2 is a back-perspective view of the beverage-holding pouch with shoulder strap, where the zipper and frontal-release straps are closed.

FIG. 3 is a front view of the beverage-holding pouch with shoulder strap, where the zipper and frontal-release straps are closed.

FIG. 4 is a back view of the beverage-holding pouch with shoulder strap, where the zipper and frontal-release straps are closed.

FIG. 5 is a right-side view of the beverage-holding pouch with shoulder strap, where the zipper and frontal-release straps are closed.

FIG. 6 is a left-side view of the beverage-holding pouch with shoulder strap, where the zipper and frontal-release straps are closed.

FIG. 7 is a bottom view of the beverage-holding pouch with shoulder strap, where the zipper and frontal-release straps are closed.

FIG. 8 is a top view of the beverage-holding pouch with shoulder strap, where the zipper and frontal-release straps are closed.

FIG. 9 is a front-perspective view of the beverage-holding pouch without shoulder strap, where the zipper and frontal-release straps are open.

FIG. 10 is a perspective view of the beverage-holding pouch without shoulder strap, where the zipper and frontal-release straps are open.

FIG. 11 is a front view of the beverage-holding pouch without shoulder strap, where the zipper and frontal-release straps are open.

FIG. 12 is a back view of the beverage-holding pouch without shoulder strap, where the zipper and frontal-release straps are open.

FIG. 13 is a right-side view of the beverage-holding pouch without shoulder strap, where the zipper and frontal-release straps are open.

FIG. 14 is a left-side view of the beverage-holding pouch without shoulder strap, where the zipper and frontal-release straps are open.

(Continued)

FIG. 15 is a bottom view of the beverage-holding pouch without shoulder strap, where the zipper and frontal-release straps are open.

FIG. 16 is a top view of the beverage-holding pouch without shoulder strap, where the zipper and frontal-release straps are open; and,

FIG. 17 is an exploded view of the parts that form the beverage-holding pouch without shoulder strap, where the zipper is closed.
